UNITED STATES PATENT OFFICE.

HARRY L. JOHNSON, OF BATTLE CREEK, MICHIGAN, ASSIGNOR TO JOHNSON AUTOMATIC SEALER COMPANY, LTD., OF BATTLE CREEK, MICHIGAN.

CARTON-SEALING MACHINE.

1,052,666.

Specification of Letters Patent.

Patented Feb. 11, 1913.

Original application filed August 4, 1908, Serial No. 446,893. Divided and this application filed January 18, 1910. Serial No. 538,776.

To all whom it may concern:

Be it known that I, HARRY L. JOHNSON, a citizen of the United States, residing at the city of Battle Creek, in the county of 5 Calhoun, State of Michigan, have invented certain new and useful Improvements in Carton-Sealing Machines, of which the following is a specification.

This invention relates to improvements in 10 carton sealing machines.

My invention relates particularly to conveyers for carton sealing machines of the type shown in my application for Letters Patent filed August 4, 1908, Serial No. 15 446,893, of which application this application is a division.

The main object of this invention is: to provide in a carton sealing machine an improved conveyer mechanism by means of 20 which the cartons are effectively supported and carried along to be acted upon by the sealing mechanism.

Further objects, and objects relating to structural details, will definitely appear 25 from the detailed description to follow.

I accomplish the objects of my invention by the devices and means described in the following specification.

The invention is clearly defined and 30 pointed out in the claims.

A structure constituting an effective and preferred embodiment of the features of my invention is clearly illustrated in the accompanying drawing, forming a part of 35 this specification, in which:

Figure 1 is a plan view of a carton sealing machine embodying the features of my invention, portions of the feed and delivery devices being broken away and the glue 40 receptacle shown in Fig. 2 being omitted. Fig. 2 is a detail vertical longitudinal section taken on a line corresponding to line 2—2 of Fig. 1. Fig. 3 is an enlarged detail vertical section taken on a line corresponding to line 3—3 of Fig. 2, showing the details of the conveyer and its support. Fig. 4 is a detail vertical section taken on a line corresponding to line 4—4 of Fig. 3, showing the details of the conveyer flights.

50 In the drawings, similar reference numerals refer to similar parts throughout the several views.

Referring to the drawing, the frame 1 of my improved carton sealing machine is pref-

erably rectangular in general form, it being 55 preferably made up of suitable longitudinal rails connected by vertical and horizontal cross pieces. I preferably support this frame in an elevated position by means of legs as 2. The mechanism is largely arranged and supported within this frame and consists of the conveyer for carrying the cartons through the flap folding and sealing mechanism. Such sealing mechanism is 60 preferably like that illustrated in my application for patent before referred to. The sealing mechanism is illustrated and will be described herein only in sufficient detail to 65 show the operative relation of the parts.

My improved conveyer comprises a propelling chain which is generally designated by the numeral 3 and which is preferably made up of the links 4 and 5, connected by suitable pivots 6. On the links 4 I mount the carton engaging carriers which preferably consist of the standards 7 having cross pieces 8 thereon. These standards are adjustably secured to the links by means of the angle shaped brackets 9. The attachment is effected by means of the securing 70 screws 10 and the set screws 11. This propelling chain is carried by the sprocket wheels 12 and 13 arranged at the front and rear, respectively, of the machine. The conveyer way is arranged above 75 the propelling chain and preferably consists of the bottom pieces 14 between which the standards 7 of the carriers project when the carriers are in their engaging or operative position. The side 80 pieces 15 are preferably located oppositely to the cross piece 8 on standards. The bottom pieces 14 project forwardly beyond the side pieces 15 at 14' to receive the cartons from the feed devices which will be herein- 85 after described. This conveyer is supported on the uprights 16 which are mounted on suitable cross pieces 17 on the main frame. (See Fig. 3). The upper reach of the propelling chain is supported between the 90 sprocket wheels 12 and 13 by means of the ways 18, in which the rollers 19, carried by the links, are arranged to travel so that the carriers are held against vertical movement 95 when in engagement with the cartons. These rollers are preferably arranged in pairs so that they also prevent the tilting of the carriers while they are in engage- 100 105

ment with or carrying the carton. The forward ends of the ways 18 are flared at 20 so that the rollers 19 readily pass into the same as they pass over the sprocket wheel 12. I thus secure a conveyer by which the cartons are carried forward to the machine in a manner which advances them positively while they are being acted upon by the flap sealing devices.

10 The sprocket wheel 13 is loosely mounted on the shaft 21 and is driven through a suitable driving connection, the details of which are not here illustrated.

15 The cartons are preferably delivered to the conveyer by means of an automatic feed which is preferably substantially the mechanism described in my application for Letters Patent filed April 14, 1908, Serial No. 426,994, for carton sealing machines and 20 preferably consists of a pair of feed belts 22 arranged with their rear ends at each side of the forward end of the bottom of the conveyer way. The top or upper planes of the feed belts being substantially the 25 same as the top of the bottom conveyer way, so that the cartons may be shifted laterally from the feed belts onto the way. The rear ends of the feed belts are supported by pulleys 23 mounted on the shaft 24, arranged transversely of the machine. As 30 these belts may extend any desired distance from the machine and be arranged so as to receive the filled cartons from a carton filling machine, or the cartons may be placed 35 thereon by hand, if desired, I do not illustrate the supplying or delivery mechanism herein. The feed belts are, however, preferably driven at a speed which exceeds somewhat the speed of the carton sealing 40 conveyer. The object of this is to secure a full supply of the cartons to the sealing mechanism. That is, that the cartons may be delivered to the sealing mechanism as rapidly as required.

45 As the cartons are carried forward by the feed belts 22 they are engaged by the stops 25 and held thereby until the stops are tripped by the shifting mechanism. These stops are substantially the same as those 50 illustrated in my application for patent referred to. To the rear of these stops I locate the laterally moving carton shifters which I designate generally by the numerals 26. The carton shifting mechanism is prefer- 55 ably that described in detail in my applica- 60 tion for patent, above referred to, of which this is a division, and I do not enter into a detailed description thereof herein. These shifters are geared or connected so that their 65 operation is properly timed with the conveyer mechanism. The driving mechanism shown being that of my application last referred to. As the cartons are shifted onto the conveyer and carried forward thereby the flaps are properly

glued and folded. The mechanism for doing this is preferably that of my said application, consisting of the rear flap folder 27, front flap folder 28, flap retainers 29, which retain the front and rear flaps in their folded positions, the flap spreaders 30 which turn the side flaps out to position to receive the glue from the glue mechanism 31, side flap turners 32 beyond the glue mechanism and the flap pressers 33 co-acting therewith. As before stated, this mechanism is shown only to show the operative relation thereof to the conveyer and therefore its details and the details of the driving or actuating mechanism are not further described herein. From the conveyer the cartons are passed to the delivery belts 34.

I have illustrated and described my improved conveyer in the construction or embodiment thereof preferred by me. I desire to remark, however, that it is capable of considerable variation in structural details without departing from my invention.

Having thus described my invention, what I claim as new and desire to secure by Letters Patent is:

1. The combination of a conveyer comprising a way having a bottom and sides, the forward end of the bottom projecting beyond said sides, the objects conveyed traveling upon said bottom; a propelling chain arranged below said way; carriers arranged on said chain to project through said bottom when in their operative position, the objects carried by said conveyer resting upon and being propelled along said bottom by said carriers, and means for feeding the objects to the said projecting end of said way bottom.

2. A conveyer comprising a way having a bottom on which the articles conveyed travel; a propelling chain arranged parallel with the bottom; carriers arranged on said chain to project above said way bottom when in operative position to engage the articles resting thereon, said articles being pushed along on said bottom by said carriers; supports for the chain links by which the carriers are carried; and ways for said supports coacting therewith to support the carriers against tilting movement while they are in their article engaging position, said carriers being mounted on said chain for tilting adjustment relative to the conveyer bottom.

3. The combination of a conveyer comprising a way having spaced bottom and side pieces, a propelling chain arranged below said way, carriers for said chain consisting of standards arranged to extend upwardly through said way bottom, cross pieces for said carrier standards arranged oppositely of said side pieces of said way, standard brackets on said chain, said stand-

ards being adjustably secured to said brackets, supporting rollers for the links by which said carriers are carried, and ways for said rollers, said rollers being arranged 5 in pairs whereby said carriers are supported and held in an upright position.

4. The combination of a conveyer comprising a way having spaced bottom and side pieces, a propelling chain arranged below said way, carriers for said chain consisting of standards arranged to extend upwardly through said way bottom, cross pieces for said carrier standards arranged oppositely of said side pieces of said way, 10 standard brackets on said chain, said standards being adjustably secured to said brackets, supporting rollers for the links by which said carriers are carried, and ways for said rollers.
- 15 5. The combination of a conveyer comprising a way having spaced bottom and side pieces, a propelling chain arranged below said way, carriers for said chain consisting of standards arranged to extend up- 20wardly through said way bottom, cross pieces for said carrier standards arranged oppositely of said side pieces of said way, and supporting rollers for the links by which said carriers are carried.

wardly through said way bottom, cross 25 pieces for said carrier standards arranged oppositely of said side pieces of said way, and brackets for connecting said carrier standards to the links of said chain, said standards being adjustably secured to said 30 brackets.

6. The combination of a conveyer comprising a way having spaced bottom and side pieces, a propelling chain arranged below said way, carriers for said chain consisting of standards arranged to extend up- 35wardly through said way bottom, cross pieces for said carrier standards arranged oppositely of said side pieces of said way, and supporting rollers for the links by 40 which said carriers are carried.

In witness whereof, I have hereunto set my hand and seal in the presence of two witnesses.
